UNITED STATES PATENT OFFICE.

JOHN F. MILLER, OF TRAIL, BRITISH COLUMBIA, CANADA, ASSIGNOR OF ONE-HALF TO
WALTER H. ALDRIDGE, OF TRAIL, BRITISH COLUMBIA, CANADA.

ANODE-MOLD.

941,796.

Specification of Letters Patent. Patented Nov. 30, 1909.

Application filed November 10, 1906. Serial No. 342,790.

To all whom it may concern:

Be it known that I, JOHN F. MILLER, a citizen of the United States, residing at Trail, British Columbia, Canada, have invented certain new and useful Improvements in Anode-Molds, of which the following is a specification, reference being had to the drawing accompanying and forming part of the same.

10 My invention relates to molds for casting anodes for use in the electrolytic refining of impure metals, for example lead, and has for its object to provide a mold in which anodes of uniform size may be cast and 15 readily removed without dismembering the mold.

The preferred form of the invention is illustrated in the accompanying drawing, in which—

20 Figure 1 is a side elevation of the mold, with a portion of one side broken away to show the interior and the formation of the joint between the two side pieces at the edges thereof. Fig. 2 is a central trans- 25 verse section of the mold. Fig. 3 is a view partly in plan and partly in horizontal section. Fig. 4 is a detail sectional view on line IV—IV, Fig. 1. Fig. 5 is a perspective view of the wedge or device used for drawing the casting from the mold.

The mold consists of three parts,—two side members, 1, 2, and the drawing wedge 3.

The side members are of a general rectangular form, but are slightly narrower at 35 their bases, to facilitate withdrawal of the casting, or anode, as will be readily understood. At the top, each member is provided with lateral extensions or wings 4, so that the anode cast in the mold will be 40 formed with wings or extensions by which it may be supported in the tank containing the electrolyte.

Near one edge of the inner face of the side member 1 is a bead or rib 5, and near 45 the opposite edge of the same side member is a similar bead or rib 6, while across the bottom of the member is a similar bead or rib 7. Between the ribs and edges are bolt holes, to receive bolts 8, which extend 50 through corresponding holes in the other side member.

The side members are assembled as shown in Figs. 1, 2 and 3, with the rib on one bearing against the inner face of the other. 55 In Fig. 1 the rib at the right edge or side

of the mold is shown in section. Around the members, between the ribs and the bolt holes, is placed a strip of soft rubber or other suitable packing, 9. When the bolts are tightened this packing is compressed, as 60 will be readily understood, making a liquid-tight joint between the members or plates.

At the top of each side member or plate are two lugs, 10, preferably beveled on their outer faces 11, as shown, to engage correspondingly beveled faces of lugs 12 formed at the ends of the drawing wedge or member 3, shown more clearly in Fig. 5. This member is of wedge or trapezoidal form, as shown, and fits closely the space between 70 the side plates, as shown in Fig. 2. On the inclined edges of the drawing member are shoulders 14, so that the molten metal in the mold will positively engage and take a firm hold on said member. The lugs 12 are so 75 located on the drawing member that the distance between their inner faces is but slightly greater than the distance between the outer faces 11 of the lugs 10, while the latter lugs are equidistant from the center line of the 80 mold, so that when the drawing member is inserted into the mold it will be accurately positioned at the center of the top thereof, as will be readily understood. The said drawing member is preferably of such depth 85 as to extend slightly below the bottoms of the lateral extensions 4.

The mold members 1, 2, 3, are preferably of soft, tough, gray cast-iron, free from all injurious cold-shuts or blow-holes. The inner surfaces of the side members 1, 2, are 90 perfectly plane and are made as smooth as possible. If the mold is to be used as hereinafter described, the inner surfaces of the plates 1, 2, when the molten metal comes in 95 contact therewith, must be absolutely free from pits or projections of any kind. In order to permit ready access of the dressing or planing tools to all parts of the inner surface of the member 1 the bottom rib may be 100 cut away at its ends and the openings thus made are afterward filled by small blocks 15.

The preferred way of using the mold is as follows: The mold, with the drawing member in place, is supported vertically in a suitable cooling medium, such as water, which is circulated around the mold, the latter extending a short distance above the water, say, about two inches. Molten lead or other metal for the anode is then deposited in the 110

5 mold, flowing up around and firmly embedding the drawing member 3. When the molten metal is solidified and sufficiently cooled, power is applied to the drawing member, as by means of an eye, 16, securely fastened thereto, and the casting is drawn out, after which the drawing member can be removed laterally from the casting and reinserted in the mold for the next molding 10 operation.

10 From the foregoing it will be seen that the mold is simple and comparatively inexpensive, and that the anodes are all of the same size and shape.

15 The mold may of course be made in other forms than that shown and may be modified in various ways without departure from its proper scope as defined by the appended claims.

20 What I claim is:

1. A mold for casting anodes, comprising in combination, a pair of spaced side members or plates, and a drawing member positioned in the top of the mold and provided 25 with means for positive engagement with the molten metal in the mold, whereby when the metal is solidified the casting can be drawn out of the mold by means of the said drawing member, as set forth.

30 2. A mold for casting anodes, comprising in combination, a pair of side members or

35 plates separated by a rib extending around the sides and bottom of the mold and spaced from the edges thereof, a strip of yielding material outside of the rib, and a series of 35 clamping devices engaging the side plates or members outside of the said rib and binding the plates firmly together, as set forth.

3. A mold for casting anodes, comprising in combination, a mold having an open top, 40 and a drawing member supported in the top of the mold and provided with shoulders on its ends to be engaged by the molten metal, whereby when the metal is solidified the casting can be drawn out of the mold by 45 means of the said drawing member, as set forth.

4. A mold for casting anodes, comprising in combination, a mold having an open top and having spaced lugs on its top, and a 50 drawing member extending into the open top of the mold and constructed so as to be positively engaged by the molten metal therein and provided with lugs adapted to engage the lugs on the top of the mold to accurately position the said drawing member, as set forth.

JOHN F. MILLER.
